UNITED STATES PATENT OFFICE.

CHARLES O. ROGERS, OF ATLANTIC, MASSACHUSETTS, ASSIGNOR TO CHARLES J. JAGER COMPANY, OF BOSTON, MASSACHUSETTS, A CORPORATION OF MASSACHUSETTS.

POWER PUMPING UNIT.

Application filed March 2, 1922 Serial No. 540,587.

To all whom it may concern:

Be it known that I, CHARLES O. ROGERS, a citizen of the United States, residing at Atlantic, county of Norfolk, State of Massachusetts, have invented an Improvement in Power Pumping Units, of which the following description, in connection with the accompanying drawing, is a specification, like characters on the drawing representing like parts.

This invention relates to a power pumping unit or a self contained structure comprising a pump and a motor for operating the pump. Such a unit renders the pump capable of being set up in any desired locality and to be readily operated under power to pump a large volume of water.

The object of the invention is to present a unit of this character which shall be compact, and in which the elements shall be so arranged as to present a well balanced structure having a low center of gravity.

The object of the invention is further to provide a construction in which a standard form of hand pump may be utilized in the unit, and in which the construction added to the pump results in a complete structure of power pumping unit which is well balanced and has a low center of gravity.

These and other features of the invention will appear more fully from the accompanying description and drawings, and will be particularly pointed out in the claims.

In the drawings:

Fig. 1 is a side elevation, partially broken away, of a power pumping unit embodying a preferred form of the invention.

Fig. 2 is a right hand end elevation of the construction shown in Fig. 1.

Fig. 3 is a top plan view of the supporting frame forming a part of the unit.

The pump employed in this unit may be of any standard construction and its mechanism forms no part of the present invention. A standard form of hand pump is illustrated herein. The frame of such a pump commonly includes a casing comprising a base 1 and a top section 2, secured together by bolts 3 passing through lugs 4 formed on the two parts of the casing. The pumping member may be of any type and is herein shown as

of the diaphragm type. The flexible diaphragm 5 is clamped at its periphery between the casing parts 1 and 2. The central portion of the diaphragm is clamped between metal rings 6 and 7 in which is mounted the discharge valve 8. The clamping bolts 9 for these rings extend upward and support a cross head 10. The inlet of the pump 11 is provided with a suction valve 12 and the discharge outlet is through a spout 13 at one side of the top casing 2. Such a hand pump is usually operated by a handle engaging the cross head so that when the handle is rocked, water is drawn in from the inlet 11 and pumped up through the diaphragm valve 8 and out over the spout 13.

In the present invention there is provided a supporting frame 14 shown separately in Fig. 3. This frame is secured in super-imposed vertical relation to the pump casing and provides the support for the motor and connections necessary to complete the power pumping unit.

This supporting frame comprises a bed plate 15 and preferably a depending hollow base 16. The hollow base enables the frame to fit well down over the pump casing and be secured to the pump casing intermediate its ends as upon the lugs 4. In the construction illustrated the supporting frame is of generally rectangular shape and the hollow depending base 16 is provided with a bottom flange 17 cut away to fit closely against the exterior surface of the top casing 2 of the pump. This flange rests upon the lugs 4 and may be secured in position by the bolts 3, suitable apertured bosses 18 being provided in the bottom flange for that purpose. In the construction illustrated there are four sets of lugs 4 arranged in substantially diametrically disposed pairs but the supporting frame is connected to but three of these pairs because at the fourth position the frame is cut away as shown at 19 to provide for the spout 13.

The supporting frame at one side of the pumping member is provided with a flat horizontal surface upon which the motor is secured. This motor may be of any desired character but is shown as an internal combustion engine of standard type. This

2
engine comprises a casing 20, a cylinder 21, crank shaft 22, and a crank casing 23 containing a fly wheel. The motor is preferably mounted in inverted position, that is, 5 with the crank shaft uppermost, thus bringing the center of gravity of the motor as low as possible.

The motor is balanced with respect to the pumping member by a crank shaft 24 and 10 connecting parts. This crank shaft 24 extends transversely of the supporting frame and is mounted in bearing blocks 25 bolted at 26 to the frame.

The motor usually runs at a speed much 15 greater than that at which the pump may be efficiently operated. Consequently reduction driving connections are provided between the motor and crank shaft 24 and such driving connections are herein shown 20 as a system of gears. These gears are also arranged in balanced relation with respect to the pumping member. In the construction illustrated the shaft 22 of the motor is provided at the rear with a pinion 27 meshing 25 with a gear 28 on an auxiliary shaft 29. A pinion 30 on the shaft 29 in turn meshes with a large gear 31 on a shaft 32 extending transversely of the frame intermediate and parallel to the shaft 22 of the motor and 30 the crank shaft 24. At the front the shaft 32 carries a pinion 33 meshing with a large gear 34 on the front end of the crank shaft 24. This system of gearing is so arranged 35 that the pinions and gears in the rear substantially balance the pinion and gear at the front with relation to the vertical axis of the pumping unit.

In order to provide a connection from the pumping unit to the crank shaft 24 and 40 maintain a low center of gravity, this invention makes use of a walking beam construction. Thus the connecting parts which are comparatively light, enable the motor to be set as low as possible. In such a construction a vertical post 35 is supported in 45 a boss 36 formed at the side of the supporting frame. To the top of this post is pivoted at 37 a walking beam 38 which extends centrally above the pumping member or axis 50 of the pumping unit to a point above the crank shaft 24. This walking beam is linked to the crank of the crank shaft 24 by a link 39 pivoted at 40 to the walking beam. The walking beam is also linked to the cross head 55 10 of the pumping member by a link 41 pivoted at 42 to the cross head and at 43 to the walking beam.

It will thus be seen that the invention presents a self contained structure which may 60 be readily transported from place to place and set up at any desired location and at once put in operation upon the operation of the motor. It will be seen that the construction is such as to have a very low center 65 of gravity, and that the various elements are

so disposed with respect to the central vertical axis, as to be in substantial balance. Thus the pump will function without the necessity of being held down or secured in place and without danger of being tipped over. The supporting frame while disposed well down on the pump casing, is nevertheless so arranged as to permit the discharge from the usual spout 13 arranged at the top of the pump casing. The entire structure is rigid and compact and of simple and durable construction.

If, for any reason, it is desired to use the pump as a hand pump the link 41 may readily be disconnected from the cross head 10 80 and the supporting frame disconnected from the lugs 4.

Having thus described my invention, what I claim as new and desire to secure by Letters Patent, is:

1. A power pumping unit comprising a pump casing, a movable pumping member therein, a supporting frame in superimposed vertical relation to the pump casing, a motor mounted on the frame at one side of the 90 pumping member, a crank shaft mounted on the frame at the opposite side of the pumping member, reduction driving connections from the motor to the crank shaft, a walking beam extending above the motor, centrally above the pumping member and above the crank shaft, pivoted to the frame, linked to the crank shaft and linked to the pumping member whereby the frame and parts supported thereby have a relatively low center of gravity and are substantially balanced with respect to the vertical axis of the pump casing.

2. A power pumping unit comprising the construction defined in claim 1 in which the 105 supporting frame is detachably secured to the pump casing and the link connection on the walking beam is detachably secured to the movable pumping member whereby the supporting frame and the parts supported thereby may be attached to and removed from a standard pump.

3. A power pumping unit comprising the construction defined in claim 1 in which the supporting frame includes a hollow depending base fitted over the pump casing and enabling the supporting frame to be secured to the pump casing intermediate its end.

4. A power pumping unit comprising the 115 construction defined in claim 1 in which the motor is an inverted internal combustion engine whereby the center of gravity of the motor is brought close to the supporting frame.

5. A power pumping unit comprising the construction defined in claim 3 in which the depending base is cut away at one side so as not to interfere with a high discharge opening in the pump casing.

6. A power pumping unit comprising the construction defined in claim 1 in which the reduction driving connections comprise a shaft intermediate the motor and crank shaft and parallel with the latter, a large gear at one end of said shaft driven from the motor, a pinion at the opposite end of

said shaft and a large gear on the crank shaft driven from the pinion and balancing the large gear on the intermediate shaft. 10 In testimony whereof, I have signed my name to this specification.

CHARLES O. ROGERS.
